UNITED STATES PATENT OFFICE.

ROBERT W. MILLS, OF BENTON HARBOR, MICHIGAN.

HAMMER OR THE LIKE.

Application filed June 4, 1925. Serial No. 26,222.

This invention relates to hammers and similar tools and more particularly to means whereby the handle can be attached firmly to the head of the tool without danger of separating while the tool is in use.

A further object is to provide fastening means which can be applied readily and will be held positively against loosening after being properly adjusted.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred forms of the invention have been shown.

In said drawings,

Figure 1 is a view partly in section and partly in elevation of a hammer having the present improvements combined therewith.

Figure 2 is a perspective view of one of the fastening elements used therewith.

Figures 3, 4, and 5 are perspective views of other parts of the fastener.

Figure 6 is a section through a portion of the handle of the tool showing a modified fastening means.

Figure 7 is a view partly in elevation and partly in section of a portion of a hammer showing another means for fastening the handle to the hammer head.

Figure 8 is an end view of a portion of the tool shown in Figure 7, the fastening means being removed.

Referring to the figures by characters of reference 1 designates the head of a hammer or other like tool in which is formed a transverse dovetail groove 2. This groove is adapted to receive the dovetail end 3 of a handle member 4 said end being provided with a reinforcing sleeve or ferrule 3'. This handle member is gradually reduced or tapered toward that end thereof remote from the dovetail 3 and said reduced end abuts against the small end of another tapered handle section 5 having a recess 6 in its large or exposed end. The two handle members are held against relative rotation by dowels 7 projecting into the ends of the

handle members as shown. The handle members are also provided with registering central bores 8 which align with a similar bore 9 extending through the head 1. A recess 10 is provided in the head at the outer end of the bore 9 and is preferably angular.

A bolt 11 is adapted to be inserted into the registering bores 8 and 9. This bolt has a head 12 designed to bear against the head 1 and is also provided with an angular portion 13 fitting close to the head and adapted to be seated snugly within the recess 10, thereby to hold the bolt against rotation within the head 1. One end of the bolt is screw threaded, as shown at 14, this end projecting into the recess 6. It is here extended through a disk 15 having prongs 16 extending therefrom and adapted to project into the inner wall of the recess 6. On this disk are provided outstanding ears 17 arranged in pairs and seated between these ears are arms 18 radiating from a washer 19 mounted on the bolt and bearing against the disk 15. The ends of the arms 18 project beyond the disk 15 where they can be engaged by teeth 23 upon one face of a nut 22. Consequently as the nut is tightened these teeth will snap into engagement with one or more of the arms 18 and hold the nut against rotation relative to washer 19. As the washer 19 is interlocked with disk 15 and this disk, in turn, is anchored to the handle member 5, it will be apparent that the different parts can not become detached accidentally. If desired recesses 25 may be formed in the periphery of nut 22 for the reception of a spanner wrench used for tightening the nut. With the parts thus properly secured they will all be held together firmly and it will become impossible for them to separate accidentally. If desired a washer 21 can be substituted for washer 19. This washer has tongues or ears 20 struck therefrom, leaving openings 24 into which teeth 23 can snap. Tongues or ears 20 will in turn engage the disk 15 and hold the washer 21 against retrograde movement.

Instead of utilizing the disk 15 and the washer 19, the modified arrangement illustrated in Figure 6 can be employed. In this structure the washer 26, which corresponds with the washer 21, can have tongues 27 struck therefrom adapted to project into the handle member 28. A nut 29 corresponding with the nut 22 can then be

screwed onto the end of the bolt 30 and the feet 31 thereon will snap into one or more of the openings 32 formed in the washer, thus holding the nut against retrograde movement.

Another modified form of device has been illustrated in Figure 7. In this structure the handle member 33 has a bore 34 extending thereinto from its dovetail end 35 and anchored in this bore is a metal core 36 in the form of an interiorly screw threaded tube having anchoring prongs 37 at its inner end which will spread into the handle member when the core is forced into bore.

15 A circular recess 38 is formed in the outer face of the head 39 of the tool and is concentric with the bore 40 which extends through the head 39. Grooves 41 radiate from this bore through the recess at 38 as shown especially in Figure 8 and these grooves are adapted to receive arms 42 radiating from a washer similar to that illustrated in Figure 3. The ends of these arms project partly across the recess 38 where they will be engaged by tongues 43 struck back from a washer 44 corresponding with the washer 21 shown in Figure 4. A bolt 45 is adapted to be screwed into the core 36 after being inserted through bore 40. This bolt 30 has a head 46 provided with an angular extension 47 adapted to fit snugly within the central opening in washer 21. Thus when the bolt is screwed into the core 36 the parts will be pressed firmly together and the tongue 35 or tongs 43 will snap into engagement with

one or more of the arms 42 thereby holding the bolt against retrograde movement.

It is to be understood of course that the improvements herein described can be applied to different kinds of tools made up of handles and heads attached thereto.

What is claimed is:

The combination with a tool having a dovetail groove in one face, a handle having one end insertible into the groove, there being a longitudinal bore within the handle and through the grooved tool, one end of the bore being counterbored, of a bolt removably seated within the bores having one end portion engaging the tool to hold the bolt against rotation, the other end portion of the bolt being screw threaded and extending into the counterbore, a disk loosely fitted on the bolt and having projections engaging a wall of the counterbore, said bolt being 50 slid able in the disk, spaced projections on one face of the disk, a washer loosely mounted on the bolt and having radial arms held against rotation by the projections on the disk, said arms projecting radially beyond 55 the disk, a nut engaging the threaded portion of the bolt and seated in the counterbore, and teeth upon the nut for snapping into engagement with the projecting ends of the arms, thereby to hold the nut against 60 retrograde movement.

In testimony that I claim the foregoing as my own, I have hereto affixed my signature.

ROBERT W. MILLS.
